CLAIM

The ornamental design for a mirror, as shown and described.

DESCRIPTION

FIG. 1 is a front, left and top perspective view of a mirror, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, left, top perspective view of the mirror in a bent position.

FIG. 10 is a front, left, and top perspective view of the mirror in a straight position.

FIG. 11 is a front, left, and top perspective view of the mirror shown in another bent position, shown in an environment of use.

FIG. 12 is an enlarged detailed view of encircled area 12 in FIG. 1; and,

FIG. 13 is an enlarged detailed view of encircled area 13 in FIG. 3.

The broken lines show portions of the mirror that form no part of the claimed design. In FIG. 11, the pole shown in broken lines shows environment and form no part of the claimed design.

The dot-dashed lines in FIGS. 1, 3, 12 and 13 illustrate the border of enlarged detailed views and form no part of the claimed design.
